UNITED STATES PATENT OFFICE

2,462,073

MINIATURE RAILROAD RAIL

Edward J. Daughton, Elmwood Park, Ill.

Application September 15, 1947, Serial No. 774,134

3 Claims. (Cl. 191—22)

1

This invention relates to new and useful improvements and structural refinements in rails for miniature railroads, more specifically, miniature railroads of the electric type, which usually embody various types of electrically actuated accessories, such as for example, signal lights, level crossing guards, or the like.

These accessories are, as aforesaid, electrically actuated and are usually set in operation by the passage of a train past a predetermined point on the track, for which purpose an auxiliary rail is commonly provided adjacent the track, so that it may be contacted by a cooperating collector shoe, or some other current pick-up device, provided on the locomotive or one of the cars. However, the provision of such an auxiliary rail detracts considerably from the realistic appearance of the railroad layout, particularly in instances where the so-called three-rail system of track is used, and in addition, the provision of the auxiliary rail contacting shoe on the train frequently involves complicated structural considerations.

It is, therefore, the principal object of the invention to provide a miniature railroad rail which eliminates the disadvantages above outlined by combining, as it were, the auxiliary rail with one of the traffic rails into a single unit, the appearance of which is not much different from that of an ordinary traffic rail.

A further object of the invention is to provide a railroad rail of the character described which is simple in construction, which may be easily installed in position, and which is otherwise well adapted for the purpose for which it is intended.

With the above more important objects in view and such other objects as may become apparent as this specification proceeds, the invention consists essentially of the construction and arrangement of parts as shown in the accompanying drawings in which:

Figure 1 is a top plan view of a miniature railroad track, illustrating the invention embodied therein;

Figure 2 is a cross sectional view, taken substantially in a plane of the line 2—2 in Figure 1; and

Figure 3 is a wiring diagram showing the preferred electrical connections which may be employed when the instant rail is placed in use.

Figure 4 is an end view of the rails with the bonding material removed.

Like characters of reference are used to designate like parts in the specification and throughout the several views.

2

Referring now to the accompanying drawings in detail, the invention is designated generally by the reference character 10 and embodies in its construction a railroad rail 11 consisting of a pair of complementary rail half-sections 12, 13 disposed in spaced parallel relation, as is best illustrated in Figure 2.

Each of the half-sections consists of a strip of metallic material angulated to form a hollow head portion 14, a web member 15 and a hollow flange portion 16, these portions coacting, when the half sections are placed adjacent one another to form the head, the web and the base flange of the rail, as will be clearly apparent.

A filler of suitable insulating material 17 is provided between and within the half-sections 12, 13, this filler possessing what may be referred to as bonding qualities, whereby the two half-sections are firmly and rigidly secured together.

To facilitate the bonding of the two half-sections, the longitudinal edges of the strips from which the half-sections are formed are inturned or angulated so as to provide channel-shaped bonding members 18 in the head and flange portions 14, 16, respectively, the members 18 being embedded in the filler 17, substantially as shown.

It will be apparent from the foregoing that the half-sections 12, 13, together with the insulating filler 17, assume the form of a single unit or rail, and when the invention is placed in use, this rail may be secured in the conventional manner to a plurality of sleepers 19, by means of suitable keeper plates or lugs 20 with which the sleepers are provided. Needless to say, the lugs 20 engage the flanges 16 of the rails, and the sleepers should either be formed from insulating material, or insulation should be provided at the point of contact of the rail with the sleepers and with the lugs 20, so that the half-sections 12, 13 are electrically isolated.

The rail 11 thus constitutes one of the traffic rails of the track, the remaining traffic rail 21 being of any suitable type. In the accompanying drawings, the track shown is of the "two rail type," that is to say, the train wheels in each pair are insulated one from the other, so that electric current may be delivered to the train driving motor through the medium of one rail and one wheel and returned by the second wheel and second rail. These wheels are illustrated at 22, 23 in the accompanying Figure 3.

However, it will be found that the invention will function with equal effectiveness if the so-called three rail system of track is employed.

When the invention is placed in use and elec-

trical connections are being made, reference should be had to the accompanying Figure 3, wherein 24, 25 represent a source of electric current, such as for example, the secondary terminals of a step-down transformer. The terminal 24 may be connected by means of a conductor 26 to the traffic rail 21, and if desired, a suitable rheostat 27 may be inserted in series in the conductor 26, for obvious reasons.

The second terminal 25 is, in turn, connected by a conductor 28 to the rail half-section 13, while 29 designates the train driving motor, the poles of which are connected as at 30, 31 to the wheels 22, 23, respectively.

It will be seen from the foregoing that electric current will be delivered to the motor 29 through the conductor 26, the rail 21, the wheel 22 and the conductor 30, while the return path of the current from the motor is facilitated by the conductor 31, the wheel 23, the rail half-section 13 and the conductor 28.

The various track-side accessories are represented in the wiring diagram by a signal lamp 32 which is connected to the conductor 26 as at 33, and also, to the rail half-section 12 as at 34.

It should be explained at this point that normally, the railroad track employs two rails of the type illustrated at 21, but in that portion of the track which is intended to actuate the accessories, one of the rails 21 is substituted by a suitable length of the rail 11.

Normally, the circuit through the lamp 32 is broken by the insulating filler 17 provided between the rail half-sections 12, 13, but when the train wheel 23 travels over the rail 11, the two half-sections 12, 13 are electrically united through the medium of the wheel, and as a result, electric circuit to the lamp 32 is completed and the lamp is energized.

The advantages of the invention thus become clearly apparent, but it should be understood that while in the accompanying Figure 3 a preferred wiring diagram has been shown, other suitable electrical connections may, of course, be employed.

However, the advantages of the wiring diagram illustrated are clearly apparent, since the circuit to the lamp 32 is independent from the circuit to the motor 29, and as a result, the lamp will be energized even though the motor 29 may be stationary, providing of course, that the wheel 23 electrically connects the rail half-sections 12, 13 together.

It is believed that the advantages and use of the invention will be clearly apparent from the

foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. A miniature railroad rail, comprising a pair of electrically conductive complementary rail half-sections disposed in spaced parallel relation, each of said half-sections comprising a strip angulated to form a partial hollow head portion, a web member and a hollow flange portion, in-turned bonding members provided on said head and flange portions, and a filler of insulating and bonding material provided between and within said half-sections to maintain the half-sections in rigid, spaced and insulated relationship, said bonding members being embedded in said filler.

2. A miniature railroad rail, comprising a pair of electrically conductive complementary rail half-sections disposed in spaced parallel relation, each of said half-sections comprising a strip angulated to form a partial hollow head portion, a web member and a hollow flange portion, the longitudinal edges of said strip being inturned to provide channel-shaped bonding members in said head and flange portions, and a filler of insulating and bonding material provided between and within said half-sections to maintain the half-sections in rigid, spaced and insulated relationship, said bonding members being embedded in said filler.

3. The combination of claim 1 and said in-turned bonding members including angularly bent portions integral with said head and flange portions.

EDWARD J. DAUGHTON.
